UNITED STATES PATENT OFFICE.

ELMER G. McGATH, OF LANCASTER, OHIO.

RAILROAD SIGNALING DEVICE.

No. 861,759.

Specification of Letters Patent.

Patented July 30, 1907.

Application filed April 11, 1907. Serial No. 367,625.

To all whom it may concern:

Be it known that I, ELMER G. McGATH, a citizen of the United States, residing at Lancaster, in the county of Fairfield and State of Ohio, have invented certain 5 new and useful Improvements in Railroad Signaling Devices, of which the following is a specification.

My invention relates to a railroad signaling device and has for its object, the provision of a device of this character constructed in such manner as to sound a 10 signal within the cab of a locomotive or at some other point upon a train if the engineer passes a signal that is set at the danger point.

Further objects and advantages of the invention will be set forth in the detailed description which now follows.

In the accompanying drawing: Figure 1 is a side elevation of a portion of a railway, illustrating my invention applied thereto, Fig. 2 is a sectional view through one side of the cab of a locomotive showing the signal 20 arranged therein, Fig. 3 is an underside perspective view of the running-board of a locomotive, showing the circuit closing devices, and, Fig. 4 is a detail view of a semaphore arm hereinafter described.

Like numerals designate corresponding parts in all 25 of the figures of the drawing.

Referring to the drawing, the numeral 5 designates a switch tower, arranged adjacent to which is the usual semaphore arm 6. This semaphore arm is adapted to be actuated by a handle 7 located within the switch 30 tower, said handle being connected to said semaphore arm by a connection 8. The lever 7 has connected to its outer end a wire 9 which passes over a pulley 10 and is connected to a pipe 11. The handle 7 is pivoted upon a standard 12. The pipe 11 is supported upon 35 blocks 13 and is mounted to slide there-over. At its opposite end this pipe is connected to a wire 14 which passes around a pulley 15. The end of the wire 14 is connected at 16 (see Fig. 3) to an L-shaped semaphore arm 17, said arm being pivoted at 18 to a post 19. It 40 will therefore be seen that the wires 9 and 14 and the pipe 16 form a connection between the handle 7 and the semaphore arm 17. When the semaphore arm 17 is in the dotted line position illustrated in Fig. 4, the main semaphore arm 6 is at safety. When the main 45 semaphore arm 6 is at danger, the semaphore arm 17 is at the full line position illustrated in Fig. 4, at which time the downturned end 20 of the semaphore arm 17 lies in such position that a lever 21 (see Figs. 2 and 3) which is pivoted at 22 to the underside of the running-board 50 23 of a locomotive A, will strike said portion 20 to throw the lever rearwardly if the locomotive be moving toward the right in Fig. 1, or forwardly if the locomotive be moving in the opposite direction. Z-shaped contact plates 24 are secured to the underside of the run-

ning-board and are insulated therefrom by insulating 55 blocks 25. A contact plate 26 is secured to the lever 21 and is adapted to pass under the downwardly extending portions 24' of the contact plates 24.

It is to be understood that these downwardly extending portions are resilient and that the lever 21 binds 60 frictionally between them and the underside of the running-board by virtue of which construction the lever 21 is held in the position to which it is thrown. This frictional binding of the lever 21 in the contact arms, causes said lever to come to a gradual stop. In other 65 words, the lever is cushioned as it is thrown from its central position to its limit of movement in one direction or the other.

An electric alarm such as a bell 27 is located in the cab 28 of the locomotive, as is also a source of E. M. F. 70 such as a battery 29. One pole of this battery is connected by a conductor 30 with one of the poles of the bell. The opposite pole of the bell is connected by a conductor 31 with the contact plate 26. A conductor 32 connects the opposite pole of the battery with one 75 of the contact plates 24. A second conductor 33 leads from the conductor 30 to a second signal 35 which may be located at any desired point upon the train as in the car B. The contact plate 26 is connected with the opposite pole of the signal bell 35 by a conductor 36. A conductor 37 connects the conductor 32 and the other contact plate 24. A rod 38 extends from the lever 21 and is connected to a lever 39 which is pivoted at 40 and is located within the cab 28, this lever rendering it possible for the engineer to throw 85 the lever 21 to its central position, or until it stands at right angles to the track and in position to strike the downwardly extending portion 20 of the semaphore arm 17. When the main semaphore arm 6 is at caution, the semaphore arm 17 occupies a position midway between the full line position and the dotted line 90 position of Fig. 4.

The operation of the device is as follows: When the operator moves the handle 7 to set the arm 6 at danger, the same movement sets the arm 17 at danger, this arm 95 17 being located some distance from the arm 6. I prefer to employ a tube 11 as the major part of the connection between these two arms, for it is not subject to as great expansion and contraction as a solid rod, nor does it sag and stretch as does a wire. However, it is 100 to be understood that any form of connection between the arm 17 and the handle 7 may be employed. When in the forward movement of the locomotive the lever 21 strikes the portion 20 of the arm 17, this lever is thrown over until the plate 26 is brought into contact 105 with the portion 24' of the rearmost contact plate 24. The circuit is then completed as follows: From one pole of the battery 29 through the conductor 30, signal

27, conductor 31, contact plate 26, the rearmost contact plate 24 and conductors 37 and 32 back to the positive pole of the battery. At the same time the circuit is completed to the signal 35 from the positive side of the battery through the conductors 32 and 37; contact plate 26, conductor 36 and from the signal 35 by conductor 33, back to the negative pole of the battery. When the engine is running backwards, the lever 21 will of course be thrown over into engagement 10 with the front contact plate 24. At this time the circuit will be completed from the positive side of the battery through the conductor 32 to the front contact plate 24, thence through contact plate 26 and conductor 31 to the bell 27. The opposite pole of the bell is connected 15 to the negative side of the battery by the conductor 30 as hereinbefore set forth. At this time the circuit to the signal 35 is completed from the positive side of the battery to the conductor 32, foremost contact plate 24, contact plate 26, conductor 36 and from the bell 35 20 by the conductor 33 to the negative side of the battery. By having the lever 21 and the contact arms 24 mounted upon the underside of the running-board, these contact points are protected from the weather and will not become clogged by sleet or snow. After the lever 25 21 has been thrown to its limit of movement in either direction, the contact plates 24' will frictionally engage and hold it in position until the engineer positively disengages it and moves it to its central position by operating the lever 39. Not only will the lever 21 30 strike the arm 20 of the semaphore 17 when this arm is set at danger, but the lever 21 will strike the upper left-hand portion of said semaphore when said semaphore is set at caution. The sounding of the signals notifies both the conductor and the engineer that the 35 train has passed a signal set at danger. It will therefore be impossible for the engineer to pass a danger signal without being apprised of the fact no matter how dark, stormy or foggy the night may be.

From the foregoing description, it will be seen that 40 simple and efficient means are herein provided for accomplishing the objects of the invention, but while the elements shown and described are well adapted to serve the purposes for which they are intended, it is to be understood that the invention is not limited to the 45 precise construction set forth, but includes within its

purview such changes as may be made within the scope of the appended claims.

What I claim, is:

1. In a device of the character described, the combination with the main semaphore arm, of an auxiliary semaphore arm, connections between the main and auxiliary semaphore arms to cause the auxiliary semaphore arm to move in unison with the main semaphore arm, a lever pivoted to the underside of the running-board of a locomotive, a contact plate also carried by the underside of the running-board of a locomotive, said lever being adapted to strike against the auxiliary semaphore arm and to be thereby thrown into contact with the contact plate, and an electric signal located in the locomotive cab, and connections between said lever and said contact plate to said signal whereby the movement of the lever is adapted to complete an electric circuit to said signal, and manually operable means controllable from the cab for throwing said lever out of engagement with said contact plate. 50

2. In a device of the character described, the combination with a main semaphore arm, of an auxiliary semaphore arm, connections between the two to cause them to move in unison, a lever pivoted to the underside of the running-board of a locomotive, a contact plate carried by said lever, contact plates arranged at each of the limits of movement of said lever, an electric signal, connections between said contact plates and said signal and between said lever and said signal whereby the movement of the lever in either direction completes an electric circuit to said signal, and means controllable from the cab of the 75 locomotive for moving said lever. 65

3. In a device of the character described, the combination with a main semaphore arm, of an auxiliary semaphore arm, connections between the main and the auxiliary semaphore arms to cause the auxiliary semaphore arm to move in unison with the main semaphore arm, a horizontally swinging lever carried by a locomotive, a contact plate arranged in the path of movement of said lever, said lever being adapted to strike against the auxiliary semaphore arm and to thereby be forced into contact with the contact plate, an electric signal located in a locomotive cab, and connections between said lever and said contact plate to said signal whereby the movement of the lever is adapted to complete an electric circuit to said signal, the shape of the auxiliary semaphore arm 85 being such that it lies in the path of movement of the horizontally swinging lever when the main semaphore arm is either at caution or at danger. 90

In testimony whereof I affix my signature in presence of two witnesses.
